(57) **CLAIM**

The ornamental design for a cup, as shown and described.

DESCRIPTION

FIG. 1 is a perspective view of the cup design of the present invention;

FIG. 2 is an elevational view;
FIG. 3 is an elevational view taken 90 degrees from the elevational view of FIG. 2;
FIG. 4 is an elevational view taken 180 degrees from the elevational view of FIG. 2;
FIG. 5 is an elevational view taken 180 degrees from the elevational view of FIG. 3;
FIG. 6 is a top plan view;
FIG. 7 is a bottom plan view;
FIG. 8 is a perspective view of another embodiment of the design of the present invention;
FIG. 9 is an elevational view of the embodiment of FIG. 8;
FIG. 10 is an elevational view taken 90 degrees from the view of FIG. 9;
FIG. 11 is an elevational view taken 180 degrees from the view of FIG. 10;
FIG. 12 is an elevational view taken 180 degrees from the view of FIG. 9;
FIG. 13 is a bottom plan view of the embodiment of FIG. 8;
FIG. 14 is a top plan view of the embodiment of FIG. 8;
FIG. 15 is a perspective view of another embodiment of the design of the present invention;
FIG. 16 is an elevational view of the embodiment of FIG. 15;
FIG. 17 is an elevational view taken 90 degrees from the view of FIG. 16;
FIG. 18 is an elevational view taken 180 degrees from the view of FIG. 17;
FIG. 19 is an elevational view taken 180 degrees from the view of FIG. 16;
FIG. 20 is a top plan view of the embodiment of FIG. 15;
FIG. 21 is a bottom plan view of the embodiment of FIG. 15;
FIG. 22 is a perspective view of another embodiment of the design of the present invention;
FIG. 23 is an elevational view of the embodiment of FIG. 22;
FIG. 24 is an elevational view taken 90 degrees from the view of FIG. 23;
FIG. 25 is an elevational view taken 180 degrees from the view of FIG. 23;
FIG. 26 is an elevational view taken 180 degrees from the view of FIG. 24;
FIG. 27 is a top plan view taken 180 degrees from the view of FIG. 22; and,
FIG. 28 is a bottom plan view of the embodiment of FIG. 22.
